(57) **CLAIM**

The ornamental design for a box container for a bag, as shown and described.

DESCRIPTION

FIG. 1 is a plan view of a box container for a bag showing my new design in assembled condition;

FIG. 2 is a front perspective view thereof in unassembled condition;

FIG. 3 is a rear perspective view thereof;

FIG. 4 is a plan view of a second embodiment of a box container for a bag showing my new design in unassembled condition;

FIG. 5 is a front perspective view thereof in assembled condition; and,

FIG. 6 is a rear perspective view thereof.

The straight broken lines shown in FIGS. 1 and 4 represent folding areas, the triangular broken line in FIGS. 4 and 5 represents a perforation.
